UNITED STATES PATENT OFFICE

156,683

BUILDING STRUCTURE

George D. Tesch, Chicago, Ill.

Application April 8, 1946, Serial No. 128,368

Term of patent 14 years

(Cl. D13—1)

To all whom it may concern:

Be it known that I, George D. Tesch, a citizen of the United States of America and a resident of the city of Chicago, county of Cook, State of Illinois, have invented a new, original, and ornamental Design for a Building Structure, of which the following is a specification, reference being had to the accompanying drawing, forming a part thereof.

In the drawing,

Figure 1 is a front elevational view of the building structure showing my new design.

Fig. 2 is a top plan view thereof, the entrance projection shown in Figs. 1 and 3 being omitted for convenience of illustration.

Fig. 3 is a horizontal sectional floor plan view

as seen in a plane substantially on line 3—3, Fig. 1.

Fig. 4 is a vertical sectional view in planes represented by line 4—4, Fig. 3.

I claim:

The ornamental design for a building structure, substantially as shown and described.

GEORGE D. TESCH.
